UNITED STATES PATENT OFFICE.

ROBERT W. HAMILTON, OF PROVIDENCE, RHODE ISLAND.

EMBLEM HOLDER.

Application filed August 10, 1922. Serial No. 580,902.

To all whom it may concern:

Be it known that I, ROBERT W. HAMILTON, a citizen of the United States, residing at Providence, in the county of Providence and State of Rhode Island, have invented new and useful Improvements in Emblem Holders, of which the following is a specification.

This invention relates to certain new and useful improvements in emblem holders and the primary object thereof is to provide a device for connecting an emblem, locket or other article of jewelry or the like to a chain so as to prevent loss of the article as well as to assure of its securement to the chain at a predetermined point on the latter.

A further object of the invention is to provide a device of this character which can be easily and quickly operated to apply same to or release same from a chain or the like and which at the same time is positive in its holding action.

The invention still further aims to provide a device which is of simple and economical construction and has still further and other objects, which will be later set forth and manifested in the course of the following description.

In the drawings:

Figure 1, is a front elevation of the invention;

Figure 2, is a section on line 2—2 of Figure 1, and

Figure 3, is a section on line 3—3 of Figure 1.

In proceeding in accordance with the present invention, a tubular body 1, is employed which has a closed end 2 to which latter a ring or eye 3 is secured, in order to provide a means of attachment for an emblem, locket or other article of jewelry or personal adornment, indicated at 4 in the drawings.

A substantially U-shaped member 5 has the free ends of its arms 6 secured to the opposite sides of the body 1, in any suitable manner, such as by soldering, the arms being longitudinally slotted as shown at 7. The closed end of the member 5 forms a rigid jaw which engages one side of the chain or the like, indicated at 8. The opposite side of the chain 8 is engaged by a slideable tensioned jaw 9 and acts to normally urge the jaw 9 outwardly away from the body 1. The jaw 9 has a lateral perforation therethrough receiving a pin 12 there-

in, which latter may be rigidly secured in any desired or suitable manner, the ends of the pin projecting through the slots 7, so as to be capable of engagement by or with the fingers to thus slide the jaw 9 inwardly or away from the chain so as to release the latter.

The U-shaped member 5 is formed of a strip of metal bent into U-shape, and consequently it has open sides through which the chain may be readily passed in securing the device thereto.

In operation, the pin 12 is grasped by the fingers and the jaw 9 then slid downwardly or toward the body 1, whereupon the chain is passed through the open sides of the U-member 5 and the device positioned at the desired point on the chain 8, following which the pin is released and the jaw 9 is then caused to grip the chain by virtue of the tension exerted thereon by the spring 11. The chain is thus gripped between the jaw 9 and the jaw formed by the closed end of the member 5.

By releasing the jaw 9 from engagement with the chain, the device may be disengaged from the chain, or moved to any desired position on the latter and again held by permitting the jaw to again engage the chain.

It will thus be seen that the chain is literally pinched between the two jaws and the device consequently held in fixed relation to the chain and at any predetermined point thereon, preventing loss or displacement of the article with respect to the chain.

Having thus described my invention, what I claim as new and desire to secure by Letters Patent is:—

1. In a jewelry holder for chains, a tubular body closed at one end, means to attach an article of jewelry to the closed end of the body, a jaw having a tubular shank slideable in the tubular body, a coil spring in the shank abutting the jaw and the closed end of the body at its ends, a pin carried by the jaw, and a U-shaped member having its arms secured to opposite sides of the tubular body and having longitudinal slots in its arms receiving the ends of the pin therethrough, the closed end of the U-member forming a jaw and the sides of the member being open to allow the chain to be passed therethrough and engaged with 110 and between the two jaws.

2. In a jewelry holder for chains, a U-

shaped member having a fixed jaw with open sides to receive the chain therethrough and a spring tensioned jaw carried by the body and formed to engage the chain to hold the latter against the fixed jaw.

3. In a jewelry holder for chains, a body, a U-member having its arms secured to opposite sides of the body, and a spring pressed jaw slidably carried by the body 10 to impinge the chain between the closed end of the U-member and the jaw.

4. In a jewelry holder for chains, a body, a U-member having its arms secured to

opposite sides of the body, and being slotted, a spring pressed jaw slideable in the body 15 and formed to impinge the chain between itself and the closed end of the U-member, and a pin carried by the jaw and extending through the slots of the U-member.

In testimony whereof I have signed my 20 name to this specification in the presence of two subscribing witnesses.

ROBERT W. HAMILTON.
